UNITED STATES PATENT OFFICE.

RALEIGH J. HIMMELRIGHT, OF NEW YORK, N. Y., ASSIGNOR TO AMERICAN ARCH COMPANY, A CORPORATION OF DELAWARE.

REFRACTORY ARCH CONSTRUCTION.

Application filed January 8, 1924. Serial No. 684,921.

My invention relates to refractory arch construction for furnaces and the like, and is more especially concerned with the support of the firebrick or tile composing the arch. I aim to make the arch strong and secure, easy to install or take down, and easy to repair by replacement of defective or deteriorated brick.

How these and other advantages can be realized through my invention in a novel manner will appear from my description hereinafter of the best construction embodying the invention that is known to me.

In the drawings, Fig. 1 shows a longitudinal vertical section through a steam boiler furnace arch conveniently embodying my invention.

Fig. 2 is a fragmentary plan view of the arch at one side wall of the furnace, which is partly broken away to show the construction more clearly.

In Figs. 1 and 2, my invention is shown as applied to the main portion 4 of the arch, between the nose 5 and the ignition arch 6,—both of which latter are composed of bricks 7 with undercut heads, arranged fanwise and supported by flanged anchor plates 8 carried by transverse channel beams 9. The main portion 4 of the arch is composed of transverse rows or bungs of hung brick 10 and filler brick 11 in alternation. As shown, the hung brick 10 are laterally rabbeted at 12, and the filler brick 11 have lateral shoulders 13 that rest on the rabbets; however, any suitable mode of interengagement may be employed. The arch 4 is sealed to the side walls by fireclay 14 or the like, as usual.

The hung brick 10 have undercut heads 15 that are engaged and supported by and between transverse supporting members 16. For each bung of hung brick 10, there is a pair of the supports 16, consisting of channel beams arranged face to face with the heads 15 resting on their lower flanges. The ends of the beams 16 extend into pockets 17 in the side walls 18 of the furnace, and rest on metal plates 19 built in to form the bottoms of the pockets. The channel beams 16 may be held in the proper relative positions in any suitable manner, to keep them from separating and releasing the brick 10. As shown, they are held by bolted clamps 20, consisting of plates 21 with their ends

turned down to engage over the backs of the channels and shorter plates 22 engaging under the upper flanges of the channels. Preferably, one beam 16 of each pair extends clear to the bottoms of the pockets 17 at both ends and is fast in the walls 18, or 60 may be built in. Its mate is preferably loose in the pockets, and so much shorter than the distance from pocket back to pocket back that after the clamps 20 have been loosened, such shorter beam 16 can be shifted 65 endwise (and swung horizontally, if need be) sufficiently to release and disengage it from the pocket 17 at one end. The end of the beam thus freed can be swung out across the furnace, and the other end then 70 withdrawn.

In installing or replacing the arch, it is possible to insert both ends of the removable beam 16 in their pockets 17, insert all the brick heads 15 of the corresponding bung 75 between the two beams, and then bring the beams together to hold the brick and tighten the clamps 20 at both ends of the pair of beams. In taking the arch down, all the brick 10 of a bung can be concurrently released in similar fashion. The pockets 17, it will be seen, afford ample room and clearance for endwise and sidewise movement of the shorter beams 16 as above described.

What I claim is:

1. A refractory arch construction comprising side walls; a pair of transverse beams supported at their ends by said side walls, one of said beams being disengagable from the walls by longitudinal movement; refractory brick cooperatively supported by said pair of beams; and detachable beam-engaging means for normally preventing the longitudinal movement of a beam as aforesaid.

2. A refractory arch construction comprising side walls; a transverse beam with its ends fast in said walls; another transverse beam supported by said walls with clearance for endwise and sidewise movement to disengage it from them and permit its removal; refractory brick engaged and supported between said beams; and means for normally preventing movement of the latter beam as aforesaid.

3. A refractory arch construction comprising pocketed side walls; a transverse beam with its ends fast in the wall pockets;

another shorter transverse beam with its ends loose in said pockets and disengagable from them; refractory brick engaged and supported between said beams; and means for normally securing the shorter beam to the other to prevent its disengagement as aforesaid.

4. A refractory arch construction comprising pocketed side walls; a pair of transverse beams supported in the wall pockets at their ends, with room for relative sidewise movement to separate them; refractory brick engaged and supported between said

beams; and means for normally holding the beams together.

5. A refractory arch construction comprising side walls; a transverse beam with its ends fast in said walls; another transverse beam supported by said walls with clearance for endwise and sidewise movement to disengage it from them and permit its removal; and refractory brick engaged and supported between said beams.

In testimony whereof, I have hereunto signed my name.

RALEIGH J. HIMMELRIGHT.
